UNITED STATES PATENT OFFICE

134,905

DESIGN FOR A DENTAL PARALLEL CAVITY FORMER

Max Jeanneret, Berne, Switzerland

Application November 6, 1941, Serial No. 104,122

Term of patent 14 years

To all whom it may concern:

Be it known that I, Max Jeanneret, a citizen of Switzerland, residing at Berne, Switzerland, have invented a new, original, and ornamental Design for a Dental Parallel Cavity Former, of which the following is a specification, reference being had to the accompanying drawing, forming part thereof.

Figure 1 is a perspective view of a dental parallel cavity former showing my new design;

Figure 2 is a perspective view of the same showing the opposite side thereof.

I claim:

The ornamental design for a dental parallel cavity former, as shown.

MAX JEANNERET.
